[57] CLAIM

The ornamental design for a portable communication terminal, as shown and described.

DESCRIPTION

FIG. 1 is a perspective view of the top, front and right side of a portable communication terminal showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the top, left side and bottom with a cover in the open position and the antenna in an upright position;

FIG. 9 is a front elevational view thereof;

FIG. 10 is a top plan view thereof; and,

FIG. 11 is a left side elevational view thereof.
